UNITED STATES PATENT OFFICE.

KARL ERICH HUMPOLETZ, OF VIENNA, AUSTRIA, ASSIGNOR TO THE FIRM OF ENZES-FELDER METALLWERKE AKT. GES., OF VIENNA, AUSTRIA, A CORPORATION OF AUSTRIA.

SMALL REFRIGERATING MACHINE.

Application filed August 24, 1923. Serial No. 659,901.

To all whom it may concern:

Be it known that I, KARL ERICH HUMPOLETZ, a citizen of the Republic of Austria, residing at Vienna, in the Republic of Austria, have invented certain new and useful Improvements in Small Refrigerating Machines, of which the following is a specification.

This invention relates to small refrigerating machines of the type in which the cooling is effected by evaporation of a condensed gas, as for instance ammonia, said gas being contained in a separate tank for the cooling medium distinct from the evaporator but may be connected with the same. The condensed gas is passed over into the evaporator, whereupon it becomes active and finally escapes from the evaporator through an outflow.

One feature of the invention consists in the arrangement of a self regulating valve between the tank containing the cooling medium and the evaporator, which automatically controls the supply of the cooling medium to the evaporator in accordance with the pressure prevailing therein. The valve is moreover exposed to the pressure of a spring adjustable from without by which the velocity of the flow may be regulated.

In order to prevent congelation of the valve controlling mechanism, said mechanism is located in a casing arranged near the cover of the evaporator, whereas the valve is arranged in the bottom of the same.

In the accompanying drawing a constructional form of the invention is shown in section. 1 designates the tank, containing the cooling medium which by means of a projection 2 is screwed into the casing 3 of the control mechanism and is provided with a valve 4 or some similar shut off member. The casing 3 is connected with the tube-shaped evaporator 5 and contains a pipe 6 conveying the cooling medium from the tank 1 to

the bottom of the evaporator. The lower end of pipe 6 can be closed by a valve 7 carried by a pipe 10 provided with openings 9 and regulated on one hand by the pressure in the evaporator, on the other hand by the pressure of a spring adjustable from without. The adjustable spring is designated by 11; it abuts at one side against a plate 13 adjustable by a micrometer screw 12, at the other side against a membrane 14 serving as

55 abutment for a bell crank lever 15 enclos-

ing a sleeve 16 of the pipe 10. The valve 7 is moreover controlled by a spring 18 acting in opposition to the spring 11 and being adjusted to a smaller tension than the latter. The casing 3 is connected to the evaporator 5 and is provided with a gas outlet 17, the bore of which is only of the width of a capillary tube at the discharge end. When the apparatus is used for cooling drinks in bottles the evaporator tube is inserted into the bottle and the valve 4 is opened. The cooling medium is conveyed into the pipe 6 and flows into the pipe 5 where evaporation takes place, valve 7 being in the open position. The vapours produced thereby ascend into the casing 3 and escape through the tube 17. The bore of said tube 17 being very narrow, the pressure in the casing 3 will soon rise and by acting upon the membrane 14 will reduce the stress exerted by the spring 11 on the lever 15. When the pressure has risen to a certain amount the action of the spring 18 exceeds that of spring 11, valve 7 is closed and remains in this position until the pressure within the casing 3 has sufficiently decreased, whereupon the described process repeats itself.

By adjusting the tension of the spring 11 by means of the screw 12 the cooling process may be so regulated that the boiling cooling medium ascends to an appropriate height in the tube 5. There is no risk at all that the cooling medium could boil over, that is to say ascend into the casing 3 in which the control mechanism is housed, owing to the narrow bore of the discharge tube and therefore congelation of the control mechanism and consequent disabling of the regulating mechanism is entirely prevented. This feature is of great importance since small refrigerating machines are only economical in case of high efficiency.

What I claim is:

1. A refrigerating machine, comprising a casing, an evaporator depending therefrom, a tube extending through the casing and leading to the lower end of the evaporator, means for admitting a cooling medium to said tube, and means controlled by the pressure of the gases of evaporation in said casing for regulating the passage of said cooling medium through the tube.

2. In a refrigerating apparatus, a casing having a closed evaporator depending there-

- from, a tube extending through the casing and to the bottom of the evaporator for delivering the cooling medium to said evaporator, a valve for controlling said tube, 45
 5 means carried by the casing and governed by the pressure of gas in said casing from the evaporator for controlling the position of said valve.
3. A refrigerating machine, comprising a 10 casing, an evaporator cylinder depending therefrom, a tube extending to the bottom of the evaporator cylinder for delivering the cooling medium thereto, a valve for closing the delivery end of said tube, a sleeve 15 connected to and operating said valve, means arranged in said casing to influence movement of the sleeve to close the valve, and means normally overbalancing said closing means to hold said valve in open position, 20 said latter means being affected by the pressure of the evaporated cooling medium to reduce its valve influencing effect, whereby to gradually balance said valve opening means to thereby permit the valve closing 25 means to act.
4. In combination, a casing, a depending cylindrical evaporator open to the casing, a tube extending longitudinally of said evaporator for delivering a cooling medium 30 to the lower end of the latter, a valve for closing the delivery end of said tube, valve operating means extended within the casing, a closing spring cooperating with said valve operating means to influence the valve 35 for closing movement, an opening spring connected with the valve operating means to normally influence the valve in valve opening direction, the force of the opening spring being greater than that of the closing spring, a diaphragm in the casing subjected to the pressure of the evaporated 40 cooling medium and acting under such pressure to counter-balance the effect of the opening spring, and means for adjusting the tension of the opening spring at will.
5. In combination, a casing, a depending cylindrical evaporator open to the casing, a tube extending longitudinally of said evaporator for delivering a cooling medium to the lower end of the latter, a valve for closing the delivery end of said tube, valve operating means extended within the casing, 45 a closing spring cooperating with said valve operating means to influence the valve for closing movement, an opening spring connected with the valve operating means to normally influence the valve in valve opening direction, the force of the opening spring being greater than that of the closing spring, a diaphragm in the casing subjected to the pressure of the evaporated cooling medium and acting under such pressure to counter-balance the effect of the opening spring, and means to influence the valve for closing movement, an opening spring connected with the valve operating means to normally influence the valve in valve opening direction, the force of the opening spring being greater than that of the closing spring, and a diaphragm in the casing subjected to the pressure of the evaporated cooling medium and acting under such pressure to counter-balance the effect of the opening spring.
6. In combination, a casing, a depending cylindrical evaporator open to the casing, a tube extending longitudinally of said evaporator for delivering a cooling medium to the lower end of the latter, a valve for closing the delivery end of said tube, valve operating means extended within the casing, 55 a closing spring cooperating with said valve operating means to influence the valve for closing movement, an opening spring connected with the valve operating means to normally influence the valve in valve opening direction, the force of the opening spring being greater than that of the closing spring, and a diaphragm in the casing subjected to the pressure of the evaporated cooling medium and acting under such pressure to counter-balance the effect of the opening spring.

In testimony whereof I have hereunto set my hand.

KARL ERICH HUMPOLETZ.
